CARPET AND RUG CLEANING DEVICE

Terrence John McCauley, Cleveland, Ohio, assignor to The Marvella Corporation, Cleveland, Ohio, a corporation of Ohio

Application December 7, 1934, Serial No. 756,487

2 Claims. (Cl. 15—128)

My invention relates, in general, to cleaning devices and more particularly to carpet, rugs, and upholstery cleaning device.

An object of my invention relates to the combination of a fluid fountain brush, together with a fluid container and flexible feeding hose for supplying fluid to the bristles of the brush.

Another object of my invention is the provision of a fluid distributing member adapted to be mounted among the bristles and arranged along the underneath bristle side of the head of the brush, the distributing member having a plurality of small outlet openings arranged in the upper longitudinal portion thereof, so that the fluid as it passes through the small openings is directed upwardly towards the underneath bristle side of the head of the brush and thereby causes the fluid to spread and uniformly feed the bristles.

Another object of my invention is the provision of so constructing the fluid distributing member that it may be conveniently mounted upon, or removed from, the head of the brush.

A still further object of my invention is the provision of a longitudinal fluid distributing member having ends which may be opened, so that a cleaning device may be passed through the longitudinal fluid distributing member.

Other objects and a fuller understanding of my invention may be had by referring to the following description and claims, taken in combination with the accompanying drawing, in which:

Figure 1 represents a longitudinal cross-sectional view of a fluid distributing member, embodying the features of my invention;

Figure 2 is a plan view of the fluid distribution member shown in Figure 1, and illustrates the location of the small outlet openings through which the fluid passes to feed the bristles of the brush;

Figure 3 illustrates a fountain brush embodying the features of my invention, and

Figure 4 illustrates the combination of a fountain brush and a supply container, embodying the features of my invention.

With reference to the drawing, my invention is shown in combination with a brush having a head 15 and bristles 16 mounted thereon. The handle 21 may be attached to the head 15 of the brush in any suitable manner, as by having the lower end of the handle fit into a suitable opening 20 in the head 15.

Mounted among the bristles and along the underneath bristles side of the head 15, is a longitudinal fluid distribution member 10, see Figure 3. An enlarged cross-sectional view of the fluid

distribution member 10 is shown in Figure 1. Attached to the fluid distributing member 10 is a vertical upright extension 11 which may be referred to as the fluid feeding member. Any suitable means may be utilized to connect the vertical feeding member to the fluid distributing member 10. In actual practice, I find that a good strong connection is effected by brazing the vertical feeding member 11 to the longitudinal distribution member 10. Accordingly, the combination of the fluid distribution member 10 and the fluid feeding member 11 constitutes a unit, which may be connected to, or removed from, the head of the brush as a single piece. As illustrated best in Figure 2, the longitudinal fluid distributing member 10 is provided with a plurality of small fluid openings 14. These small fluid openings 14 are arranged in a staggered relationship in the upper longitudinal portion of the fluid distributing member, so that, when the fluid distributing member is mounted under the head 15, the fluid, as it passes through the small staggered fluid openings, is directed upwardly towards the underneath bristles side of the head. This uniformly distributes the fluid throughout the brushes. This distribution is very essential to the successful operation of the brush, and is made possible only by reason of the fact that the small openings 14 are arranged in the upper longitudinal half of the fluid distributing member 10. As illustrated in Figure 1, each end of the longitudinal fluid distributing member 10 is provided with a screw plug 12, which may be removed when cleaning the inside of the fluid distributing member to allow a cleaning device to pass therethrough.

The head 15 of the brush is provided with an opening through which the vertical feeding member 11 is inserted. Any suitable means may be employed to hold the vertical feeding member 11 within the head 15 of the brush. To this end, I illustrate a collar 28 which rests upon the upper surface of the head 15 and which has a set screw 29 for securely holding the vertical feeding member 11 within the opening of the brush head 15. I also find that the collar 28 may be dispensed with by making the vertical feeding member 11 fit snugly within the opening of the brush head 15. When mounted, the vertical feeding member 11 extends beyond the top of the head 15 and is adapted to have the free end of the flexible hose 23 slipped over the end thereof. This allows the fluid of the container 22, which may be any suitable cleaning fluid or shampoo, to flow to the distributing member 10. A metal ferrule 24 is mounted around the free end of the flexible hose 23.

23 to keep the hose from stretching too much as it is from time to time connected to, or disengaged from, the top end of the vertical feeding member 11. The rate at which the fluid flows 5 from the container 22 may be governed by the setting of the valve 25.

When operating my device, the fluid container 22 is mounted upon a suitable support 30 which may be either a chair or a pedestal, so that the 10 cleaning fluid will flow to the distributing member 10 by means of gravity while the operator uses the brush which is uniformly supplied with the correct amount of fluid by the adjustment of the valve 25.

15 Although I have described my invention with a certain degree of particularity, it is understood that the present disclosure has been made only by way of example and that numerous changes 20 in the details of construction and the combination and arrangement of parts may be resorted to without departing from the spirit and the scope of the invention as hereinafter claimed.

I claim as my invention:

1. The combination with a fluid fountain brush 25 having a head and an opening therethrough, and bristles mounted on the head, of a longitudinal fluid distributing member disposed among the bristles and arranged along, and in close proximity to the bristle side of the head, so that the 30 upper longitudinal central portion of the fluid distributing member is positioned along close to the underneath side of the head, a fluid feeding member connected to the fluid distributing member and arranged to extend through and beyond 35 the said opening in the head of the brush, said fluid distributing member having a plurality of

small off-set openings for the fluid to pass therethrough and feed the bristles, the said openings being arranged in the upper longitudinal portion of the fluid distributing member, and off to either side of the upper longitudinal central portion of the fluid distributing member, so that the off-set outlet openings clear the underneath side of the head and so that the fluid as it passes through the small openings is directed upwardly and outwardly at an angle toward the underneath bristle 10 side of the head and thereby cause the fluid to spread outwardly upon the bristle side of the head and uniformly feed the outside bristles, as well as the inside bristles next to the fluid distributing member.

2. The combination with a fluid fountain brush having a head and bristles mounted on the head, of a longitudinal fluid distributing member disposed among the bristles and arranged along the bristle side of the head, said fluid distributing 20 member having a plurality of small offset outlet openings for the fluid to pass therethrough and feed the bristles, the said openings being arranged in the upper longitudinal portion of the fluid distributing member, and off to either side of the 25 upper longitudinal central portion of the fluid distributing member, so that the fluid as it passes through the small openings is directed upwardly and outwardly at an angle toward the underneath bristle side of the head and thereby cause the 30 fluid to spread outwardly upon the bristle side of the head and uniformly feed the outside bristles, as well as the inside bristles next to the fluid distributing member.

TERRENCE JOHN McCUALEY.
